Attorney.

UNITED STATES PATENT OFFICE.

WILLIAM M. JOHNSON, OF MOMENCE, ILLINOIS.

SHEARS-SUPPORT.

1,264,809.

Specification of Letters Patent. Patented Apr. 30, 1918.

Application filed February 13, 1917. Serial No. 148,444.

To all whom it may concern:

Be it known that I, WILLIAM M. JOHNSON, a citizen of the United States, residing at Momence, in the county of Kankakee and State of Illinois, have invented certain useful Improvements in Shears-Supports, of which the following is a specification, reference being had therein to the accompanying drawing.

10 The present invention relates to supports, and has particular reference to an improved device for supporting shears and other tools used by workmen, and which are adapted to be carried for convenient grasping.

15 It is an object of the present invention to provide a comparatively simple, light and foldable support peculiarly adapted to receive a pair of shears and hold them in position for ready grasping, and within easy 20 reach of the workman.

It is another object of the present invention to provide a support of this character provided with a supporting frame or ring having an open side which is closed by a 25 movable finger and against which the shears may be pressed and forced into the ring for engaging the shears with the support without the necessity of guiding the points of the shears into the supporting frame or ring.

30 The above and other objects and advantages of this invention will be more fully brought out in the following detailed description of the present preferred embodiment, the same being illustrated in the accompanying drawing, wherein:

Figure 1 is a face view of the device secured to a garment and supporting a pair of shears.

Fig. 2 is an enlarged face view of the device in folded position;

Fig. 3 is an edge view of the same.

Fig. 4 is a detail sectional enlarged view of the movable finger at one side of the suspension frame.

45 Fig. 5 is a perspective detail of the wedge block.

Referring to this drawing, 10 designates an attaching plate which is provided at its upper end with a tongue 11 stamped from 50 the upper end of the plate 10 and overturned against the back thereof and being bent upwardly to provide a substantially U-shaped

pocket 12 for a purpose which will herein-after appear. The bottom, or lower end of the plate 10 is provided with a longitudinally 55 extending slot 13 through which projects the shank 14 of a slide 15. The lower end of the slide 15 is overturned inwardly and is thence bent upon itself to provide a downwardly extending tongue 16 having a pocket 60 17 formed at its inner end. The pocket 12 opens upwardly and the pocket 17 opens downwardly.

A thumb nut 18 is threaded upon the stem 14 and binds against the outer face of the 65 plate 10 to secure the slide 15 in adjusted position. The slide 15 is also provided with a longitudinal slot 19 in its upper end through which projects a guiding pin 20, the latter being carried upon the plate 10 and co-operating with the stud 14 to hold the tongue 16 from swinging upon the lower end of the plate.

The plate 10 is provided intermediate its ends with a suspension frame 21 which may 75 be of any desired configuration, the frame in the present instance being shown as of rectangular form and being connected by a hinge 22 at one of its long sides to the outer face of the plate 10. The hinge 22 may have 80 a leaf portion 23 projecting through a slot formed in the middle of the plate 10 and which is secured against the rear side of the plate 10. The frame 21 is yieldingly held in outwardly swung position at right angles 85 to the plate 10, and flat against the outer face of the plate 10, by a spring 24 which is secured to the lower end of the plate 10 and extends upwardly and is offset outwardly at its upper end to provide a supporting 90 shoulder 25 against which the lower bar of the frame seats when the frame is swung outwardly. The offset portion of the spring 24 engages over the inner bar of the frame and yieldingly holds the frame in adjusted 95 position.

One side of the frame 21 is preferably open or discontinued. The open side is normally closed by a finger 26 which is pivoted as at 27 to the outer side bar of the frame. 100 A spring 28 is carried in the frame 21 and has one end bearing against the inner side of the finger 26 to normally urge it outwardly and against a shoulder 29 formed on the

- inner side of the frame. The finger 26 therefore normally closes the frame, and may be urged inwardly by pressing the shears or other article against the outer side of the finger. 5
- Preferably, the frame 21 and the finger 26 are formed of channel iron, or are substantially U-shaped in cross section. This structure provides a suitable seat for the spring 10 28, and also provides for a substantial reinforcement 30 which may be used to strengthen the frame, and which is bent to engage about the uninterrupted angles or corners of the frame.
15. The spring 24 is at one side of the plate 10, preferably remote from the spring finger 26 to permit of the uninterrupted passage of the blades of the shears when the latter are forced through the open side of the frame. The plate 10 has at its opposite side from that on which the spring 24 is mounted, a combined supporting shoulder and guide 31 which is in the form of a wedge-shaped block, the inclined face of which 20 rises from the outer edge of the plate 10 to the adjacent end of the suspension frame 21 to guide and direct the blades of the shears, and other articles, into the open side of the frame when the latter is swung outwardly.
25. This guide 31 prevents the blades of the shears from striking against the shoulder 29 or the adjacent end of the inner bar of the frame.
- As shown in the present instance, the 30 guide 31 is in the form of a single piece of sheet metal which is suitably cut and stamped to provide the inclined face and a plurality of tongues 32 by means of which the guide may be secured to the plate 10.
40. One side 33 of the guide 31 is projected inwardly and adapted for engagement with the lower face of the frame 21 when the latter is swung outwardly. This side 33 constitutes a supporting shoulder for the 45 frame and assists the spring shoulder 25 in holding the frame in proper position when the frame is submitted to strain incident to the placing and removal of the shears in and from the support.
50. To apply the device the garment 34, or the like, is provided with a pair of spaced-apart buttonholes or suitably protected openings indicated at 35 and 36 in the drawing. The tongue 11 is inserted in the opening 35 and the edge of the opening fits in the pocket 12. The thumb screw is relaxed from the plate 10 and the slide 15 is moved upwardly against the back of the plate to permit the engagement of the tongue 16 55 through the opposite opening 36. The slide 15 is now extended so as to engage the lower edge of the opening 36 in the pocket 17. The thumb screw 18 is now tightened and the slide is held securely against the plate 60.
10. The tongues 11 and 16 now firmly hold 65 the attaching plate 10 to the garment. If a pair of shears is being used and it is desired to momentarily place the same at rest or to free the hands thereof, it is only necessary to swing the shears downwardly 70 and engage the same against the open side or finger 26 of the frame, the finger 26 swinging inwardly and permitting the shears to enter the suspension frame. The shears may now be released when the same will fall through the suspension frame until the handles engage the frame to thus support the shears. The shears may be readily withdrawn by raising the same out of the frame. The finger 26 is preferably located at the 75 outer side of the frame when the latter is applied to the garment, as shown in Fig. 1.
- It is of course understood that various changes and modifications may be made in this construction without departing from 80 the spirit of the invention, such changes and modifications being restricted only by the scope of the following claims.
- Having thus described my invention, what I claim is:
1. A device as specified, comprising an attaching plate, a suspension frame pivotally mounted upon said plate and adapted to be swung into extended position, means for supporting the frame in an extended position and a spring side in said frame adapted to yield upon engagement of an article thereagainst to permit the entrance of the article into the frame. 90
2. A support as specified, comprising an attaching plate, a suspension frame mounted on the plate and having an open side, and a spring finger hinged at said side for normally closing the same. 100
3. A support as specified, comprising an attaching plate, a supporting frame hinged at one side to the plate, a spring carried by the plate and engaging said frame to yieldingly hold it in extended and folded positions, said frame being open at one side, and a yielding finger carried at said side for normally closing said opening. 105
4. A support as specified, comprising an attaching plate, a frame hinged at one side upon said plate, a spring on the plate engaging said frame to yieldingly hold the frame in folded and extended positions, and a shoulder on said spring for contact with said frame to support it when extended. 115
5. A support as specified, comprising an attaching plate provided with a rearwardly offset tongue at its upper end, a slide mounted on the lower end of said plate, means for securing the slide in adjusted position, said slide having a rearwardly offset tongue 120 extending in a direction opposite to said first tongue on the plate, said tongues being adapted for engagement through spaced 125

buttonholes, and a supporting frame carried upon the outer face of said plate.

6. A support as specified, comprising a plate, tongues carried by the plate, means for moving said tongues toward and from each other for engaging and holding the tongues in spaced-apart buttonholes, and a

movable suspension frame carried upon the outer side of the plate for the reception of an article to be suspended. 10

In testimony whereof I hereby affix my signature.

WILLIAM M. JOHNSON.
